UNITED STATES PATENT OFFICE.

HERBERT KNIGHT, OF NEW YORK, N. Y.

HEEL.

1,309,480.

Specification of Letters Patent.

Patented July 8, 1919.

Application filed March 29, 1919. Serial No. 285,960.

To all whom it may concern:

Be it known that I, HERBERT KNIGHT, a citizen of the United States of America, residing at the borough of Manhattan, city of New York, county and State of New York, have invented a new and useful Improvement in Heels, of which the following is a specification.

The invention relates to a heel possessing certain resilient qualities, and it consists of a hollow metal structure, so constructed as to provide an elastic, or spring tread, and specifically consisting of exterior supporting walls of metal with means inherent therein and integral therewith of providing a vertical give and take as the weight is imposed or removed.

Referring to the accompanying drawing which forms a part of this specification—

Figure 1, represents a vertical section of my improved heel, showing it in position, attached to a shoe.

Fig. 2, is a cross section of same on line II—II Fig. 1.

Fig. 3, is a vertical section on the line III—III Fig. 1.

Fig. 4, is a vertical longitudinal section of a modified arrangement.

Fig. 5, is a cross section on the line V—V

Fig. 6, is a vertical section on the line VI—VI Fig. 4.

In this drawing, A— represents the wall of my improved heel and B— the top lift or base piece: The wall A— which is continuous both laterally and vertically from the rand to the top lift constitutes the supporting member or structure and is formed of spring metal; that is to say, metal resilient in its nature; contracting when a load is imposed and expanding when the load is removed.

These actions are permitted by, and in fact they are the result of, not only the elastic nature of the metal, but, also by the fact that I provide, at a suitable point between the upper and lower part of the structure, an offset, or protruding member, C— formed integrally with the wall A. The vertical give and take occurs in the zone indicated by the member C.

The offset, or protuberance C subdivides the vertical wall into upper and lower sections; should there be any slight give in the

walls A the collapsibility of the structure is mainly resident in this offset or lateral extension C. Under vertical pressure the give and take at C is relatively very much greater than in the vertical walls A: in fact, I prefer to have the walls A hold to their upright form and position.

The member C is in the nature of a bellows; the corners D and E approach and recede from one another as the weight upon the upper plate F is imposed, or removed. The quality and nature of the metal employed should be such as to give just the requisite amount of spring, or rebound in the bellows, to cushion the heel and eliminate the jar or blow to the wearer and which ordinarily attaches to the employment of hard heels, such as leather or wood.

It will be noted that the bellows C extends entirely around the periphery of the heel structure and that it is of equal dimension and equal cross-section throughout its entire extent. Being circumferential and of equal strength throughout, it provides a cushion of dependable value and efficiency. As constructed also, and as shown in the drawings, the hollow interior is entirely sealed from the exterior, thereby preventing dirt and dust from entering into the hollow heel; in fact, any hollow heel structure that permits the entrance and accumulation of dust from the outside is, from the standpoint of usage, entirely valueless.

It will be noted by referring to the drawings that the space included in and by the wall —A, and the upper and lower plate F, and B, is entirely free and clear; this construction lends lightness to the heel.

Being made of metal also, the heel, as an article of manufacture and one which is intended for wide and general use, is very durable and possesses peculiar economic value in that respect.

At G— I show turned over ends at the upper part and at H— means of attaching the heel to the upper plate F, the latter being secured in and to the sole of the shoe J, in any suitable manner.

In the form shown in Figs. 1, 2 and 3, the upper ends G— of the metal walls A— are bent over and inwardly being folded at right angles to the vertical walls, and in this manner the top, side walls, and bottom plate are formed integrally; of one piece

of metal, the integral structure including the offset part C.

In the form shown in Figs. 4, 5 and 6, the part G— is bent inwardly; in the narrow heel the outwardly turned flange works to good advantage; in the wider heel, the inwardly turned flange is best.

Besides being superior to the ordinary leather heel by reason of its resilient qualities, my present invention is preferable to such a heel, or to a rubber heel, in that it will not wear off at the edges but that it will keep its form and shape at all times.

I do not claim a metal heel made of sections which telescope one over the other; the quality of give and take as the weight is imposed or removed resides, in the case of my improved heel, in the metal itself; it is, as stated, a continuous heel structure from the top to the bottom and around the entire circumference.

It will be seen, by referring to the cross sections Figs. 2 and 5, of the two different forms presented, that whereas the heel structure broadens out into the ordinary horse shoe shape at the bottom, the central or resilient zone is circular; such a structure gives a balanced and even movement, responsive to the duties expected and required.

I may provide on the upper and lower sections of the heel and exterior to the metal supporting walls A— fillers, K and L; these fillers serve to round out the structure and give a finished shape and form to the heel; the fillers can be made of leather, wood, or any other suitable material.

It will be observed by referring to the drawings, that the filler K— extends from the upper edge of the heel down to the protuberance or offset C— and that the filler L, extends upwardly from the base of the heel to C— but that neither of the fillers encroach upon the offset C— nor do they in any manner impair the freedom of the elastic movement of the offset; the compression and the rebound of the elastic offset is just the same as if the fillers were entirely absent.

Having thus described my invention, the following is what I claim as new and useful

therein and desire to secure by Letters Pat- 50 ent:

1. A hollow heel embodying supporting walls of metal having a peripheral spring portion of relatively greater resiliency, providing a cushion. 55

2. A heel for shoes embodying supporting walls of metal, with a resilient peripheral offset in said walls.

3. A hollow heel embodying supporting walls of metal, with a peripheral protuberance formed integrally with the walls, providing a cushion. 60

4. A hollow heel embodying supporting walls of metal, with an integrally formed circumferential bellows member, providing a cushion. 65

5. A hollow heel embodying metal supporting walls, with an integrally formed, partially collapsible, peripheral section.

6. A hollow heel embodying an upper and lower section providing metallic supporting walls, with a collapsible member positioned intermediate of, and formed integrally with, said sections. 70

7. A hollow heel embodying continuous vertical supporting walls of metal, with means, extending laterally from the walls and formed integrally therewith, for providing a spring tread. 75

8. A hollow heel entirely sealed from the exterior embodying metal supporting walls, with an integrally formed and relatively more resilient cushioning member. 80

9. A hollow heel embodying metal supporting walls, having a peripheral zone integral therewith and of relative greater resiliency. 85

10. A hollow heel embodying metal supporting walls, with a zone of relative greater resiliency, providing a uniformly distributed peripheral cushion. 90

11. A hollow heel embodying an upper and lower section providing metallic supporting walls, an integrally formed, and outwardly extending bellows, and exteriorly positioned fillers on the walls above and below the bellows. 95

HERBERT KNIGHT.
